UNITED STATES PATENT OFFICE

MARTIN V. KACER, OF ST. LOUIS, MISSOURI.

BOTTLE-WRAPPER.

SPECIFICATION forming part of Letters Patent No. 234,582, dated November 16, 1880.

Application filed September 6, 1880. (No model.)

To all whom it may concern:

Be it known that I, MARTIN V. KACER, of St. Louis, in the county of St. Louis and State of Missouri, have invented a new and Improved Bottle-Wrapper; and I do hereby declare that the following is a full, clear, and exact description of the same.

The object of my invention is to provide an improved wrapper for glass bottles for the purpose of obviating the danger of breakage, and also for protecting the labels from abrasion or other injury by reason of contact of the bottles with each other or with foreign objects while being handled or shipped.

My invention is more particularly an improvement in that class of bottle-wrappers which are constructed of paper or straw board, and provided with numerous indentations, forming a series of small conical projections or points on the inner side or surface of the wrappers. In practice these points soon become flattened or obliterated, because the portions which are punched and form the protruding points recede into the cavities of the indentations upon the application of slight pressure, whereby the indentations become a useless feature of the wrappers.

My improvement consists in providing a wrapper with numerous holes or perforations; which being made with a blunt-pointed instrument, the inner side of the wrapper has numerous torn fibrous projecting points, forming the irregular edges of the respective holes, and constituting a soft cushion or con- 35 surface. These points are not forced back into the holes nor completely flattened by the degree of pressure to which wrappers are ordinarily subjected, and hence the latter retain their elastic quality and protect the bottles more effectually than those having indentations. My wrapper is also provided with notched edges which interlock, thus enabling the wrapper to be easily applied to or removed from the bottle.

In accompanying drawings, Figure 1 is a 45 side view of a bottle and my improved wrapper applied thereto. Fig. 2 is a cross-section of a portion of the wrapper slightly thickened or enlarged.

The wrapper A is formed of thick paper or straw board, and will, in practice, have such size and proportions as required to adapt it for use on various kinds and forms of wine, beer, soda, and other bottles. It is provided with numerous holes, a, which are made by 50 punching the board A with a blunt-pointed instrument, (without cutting out or removing any portion of the material.) Thus there are formed numerous ragged fibrous edges and projecting points on the inner side of the 55 board, as shown in Fig. 2, and these constitute a soft cushion-like surface, that enables the board to afford an effectual protection to the bottles and labels thereof against breakage and abrasion by contact of the bottles with 60 each other and with foreign objects. The said ragged edges and points cannot be pushed back into the holes a by the pressure incident to use of the wrapper, and they hence form a 65 cushion-surface as permanent or durable as 70 the body of the wrapper itself.

The side edges of the wrapper have notches forming catches b, which are adapted to interlock, as shown in Fig. 1. Thus the wrapper may be easily and quickly applied to or 75 detached from a bottle without injuring the face of the label.

What I claim is—

The improved bottle-wrapper formed of paper-board having numerous holes with ragged 80 edges projecting on the inner side of the wrapper, as and for the purpose specified.

MARTIN V. KACER.
